UNITED STATES PATENT OFFICE.

JOSEPH GOULBOURN, OF LEICESTER, ENGLAND, ASSIGNOR TO UNITED SHOE MACHINERY CORPORATION, OF PATERSON, NEW JERSEY, A CORPORATION OF NEW JERSEY.

MECHANISM FOR FEEDING FASTENINGS.

1,408,452.

Specification of Letters Patent. Patented Mar. 7, 1922.

Application filed April 24, 1920. Serial No. 376,320.

To all whom it may concern:

Be it known that I, JOSEPH GOULBOURN, a subject of the King of England, and resident of Leicester, Leicestershire, England, 5 have invented certain Improvements in Mechanisms for Feeding Fastenings, of which the following description, in connection with the accompanying drawings, is a specification, like reference characters on the 10 drawings indicating like parts in the several figures.

This invention relates to mechanism for feeding fastenings, the illustrated embodiment of the invention being designed particularly for use in a nailing machine of the type shown in the patent to Goddu, No. 898,573, granted Sept. 15, 1908.

In the operation of a machine of the type disclosed in such patent, nails are fed to the 20 nail driving means by a slotted raceway having covers for the slots of the raceway which serve to confine the nails in the raceway and which preferably extend close to its delivery end so as to prevent the nails from being 25 improperly ejected from the raceway slots by the mechanism which controls the delivery of the nails from the raceway. It is frequently necessary that the covers be removed from over the raceway slots in order 30 to expose the nails, for example, to enable the operator to effect dislodgement of a jammed nail or other impediment to the free movement of the nails down the raceway. It is, moreover, sometimes desirable to adjust 35 the covers relatively to the raceway.

In an application of Arthur E. Jerram, Serial No. 345,764, filed Dec. 18, 1919, for machines for operating on fastenings, raceway mechanism is disclosed comprising a 40 cover movable between operative and inoperative positions on the raceway and constrained to move when shifted from operative to inoperative positions first endwise and then transversely of the raceway, thus 45 insuring that it will not interfere with the mechanism at the delivery end of the raceway.

An object of the present invention is to provide raceway mechanism of the type disclosed in the above-mentioned application, 50 which while retaining valuable features of the mechanism described in said application will be more convenient and efficient in operation.

An important feature of the invention 55 resides in the provision of an abutment spaced from the raceway and means arranged to be interposed between the abutment and the raceway for retaining the raceway cover in operative position over the raceway.

Further features of the invention pertain 60 to raceway mechanism comprising a cover mounted on the raceway for movement endwise and transversely of the raceway and an abutment serving to retain the cover 65 in operative position over the raceway and constraining the cover to move endwise before it can be swung transversely of the raceway, in which the abutment and the part of the cover co-operating therewith 70 are relatively adjustable variably to determine the position of endwise adjustment of the cover on the raceway and in which the abutment and said part are so constructed and arranged relatively to each other and 75 the cover as to cause the abutment to complete the movement of the cover transversely of the raceway upon movement of the cover endwise toward operative position.

Although the invention will be herein- 80 after described as applied to a machine for inserting loose nails of the type comprising a double raceway, that is, a raceway having a pair of slots, it is recognized that the applicability of the invention is not restricted 85 thereto but that the invention may be used with machines of other kinds for operating on fastenings including fastening inserting machines having raceways formed with a single slot only.

Other objects and features of the invention 90 will appear as the description proceeds and will be pointed out in the appended claims.

In the drawings, 95 Fig. 1 is a view in elevation of a raceway and cover mechanism for the back slot of the raceway constructed according to the invention;

Fig. 2 is a plan view of the cover mechanism for the back slot of the raceway;

Fig. 3 is a view in elevation of the raceway and the cover mechanism for the front slot of the raceway;

Fig. 4 is a view in plan of a portion of the 100 cover for the front slot of the raceway showing the means for retaining the cover in operative position over the slot;

Fig. 5 is a view in elevation of the raceway and the cover mechanism for the slots of the raceway looking toward the left in Fig. 1 and showing the raceway in cross section; and

Fig. 6 is a view in plan of a double raceway showing cover mechanism for both the front and back slots of the raceway constructed according to the invention.

10 The illustrated construction comprises a raceway 2 formed with a front slot 4 and a back slot 6 (see Fig. 6) to which nails are supplied by hoppers 7 and 8 respectively. As shown, the nails are delivered from the 15 raceway by a separator 9 to a passage in a fastening receiving member 10, a retainer 11 being provided to prevent the escape of nails from the front slot 4 when nails are being delivered from the back slot 6. The cover 20 12 for the front slot 4 is mounted for movement endwise of and transversely of the raceway 2 on a shaft 14 supported in bearings 16 and 18 in a bracket 20 secured to the front wall of the raceway. As shown, the cover 25 12 is provided with lugs 22 and 24 arranged to slide loosely on the shaft 14. A spring 26 encircling the shaft 14 between the lug 24 and a collar 28 fast on the shaft tends to move the cover 12 toward the delivery end 30 of the raceway. In order to retain the cover in operative position over the slot 4 and to constrain it to move endwise before it can be turned away from the raceway about the shaft 14, thus insuring that the cover in its 35 movements between operative and inoperative positions will not interfere with the mechanism at the delivery end of the raceway, an abutment 30 is secured to the bracket 20 in spaced relation to the raceway such as to enable the lug 24 on the cover to be 40 interposed between the raceway and the abutment. The abutment 30 (see Fig. 4) is, preferably, made wedge-shaped in horizontal cross-section and has its inner face inclined toward the raceway in the direction of 45 the delivery end of the raceway, and the contacting face 32 of the lug 24 is correspondingly inclined. The endwise movement of the cover 12 under the action of the spring 26 is limited by engagement of the lug 24 with 50 the abutment 30, and to the end that the position of endwise adjustment of the cover on the raceway may be variably determined, the abutment is adjustably mounted on the bracket 20, for example, by means of a screw and slot connection 34. Withdrawal of the 55 cover 12 from operative position is obtained by pressure of the operator's finger upon a finger piece 36 on the cover, such pressure 60 moving the cover against the action of the spring 26 until the inclined faces of the lug 24 and abutment 30 are moved out of engagement with each other, after which the cover 12 may be swung about the shaft 14, thus carrying the lug 24 behind the abutment 30 to

be held thereagainst by pressure of the spring 26 so that the cover will remain latched in retracted and outwardly swung position.

When the cover 12 is again swung toward 70 the raceway to a position such that the forward surface of the lug 24 passes from behind the rear edge of the abutment 30, the spring 26 automatically moves the cover toward the delivery end of the raceway to the 75 extent allowed by the lug 24 and the abutment. The bearings 16 and 18, as shown, are made U-shaped and in the bottom of each of the bearings is a spring-pressed plunger 36 upon which the ends of the shaft 80 14 actually rest. Threaded through the side of each bearing is a horizontal conical screw 38 with a knurled head 40. The heads 40 are formed with a series of recesses adapted to co-operate with spring-pressed 85 detents 42 housed in the bearings. The detents 42 serve by engagement with the recesses of the head 40 to hold the screws in their adjusted position. The conical end of each screw 38 presses upon the upper surface 90 of the shaft 14 in the U-shaped bearing, and by turning the screw in or out the shaft in the bearing may be pressed down more or less against the action of the spring-pressed plunger 36 at the bottom of the bearing. In 95 this way both ends of the cover are upheld yieldingly against a positive stop, that is, the conical end of the screw, and either end of the shaft may be raised or lowered without moving the other. The shaft is prevented 100 from endwise movement under the action of the spring 26 by a head or collar 43 formed on the shaft arranged to engage the side of the bearing 18.

The cover 44 for the back slot 6 of the 105 raceway 2 is carried by a housing 45 mounted for movement endwise and transversely of the raceway on a shaft 46 to which it is pinned and which is slideable and rotatable in bearings 48 and 50 on a bracket 52 secured to the back wall of the raceway. The bearing 50 is formed to provide an abutment 54 spaced from the raceway, and a block 56 adjustably connected to the housing 45 by a pin and slot connection 57 is 110 arranged to be interposed between the abutment 54 and the raceway to retain the cover 44 in operative position over the slot 6. The contacting faces of the abutment 54 and block 56 are inclined similarly to the corresponding faces of the abutment 30 and lug 24. A spring 58 encircling the shaft 46 between the bearing 48 and a collar 59 fixed to the shaft tends to move the housing 45 and cover 44 endwise toward the delivery 115 end of the raceway. The housing 45 has a finger piece 60 by which it may be moved out of operative position, this finger piece projecting into close proximity to the piece 36 on the front cover 12 so as to facilitate 120 125 130

the manipulation of the cover 44 toward and from operative position on the raceway. The movement of the cover 44 to operative position is further facilitated by disposing 5 the contacting faces of the abutment 54 and block 56 above the shaft 46, so that, when the housing 45 has been swung toward the raceway far enough to carry the forward edge of the block 56 out of engagement with 10 the rear edge of the abutment 54 and the spring 58 thereby rendered operative to move the housing 45 endwise toward the delivery end of the raceway, the abutment 54 acting on the block 56 will complete the 15 transverse movement of the housing 45 and cover 44 to operative position.

The cover 44 is constituted by a vertically disposed blade inserted in a vertical slot in the housing 45 and inasmuch as access cannot 20 readily be had to the back wall of the raceway to adjust the housing 45 the cover is rendered adjustable relatively to the housing. Preferably, the cover is mounted for adjustment in the housing so that either or 25 both of its ends may be adjusted vertically relatively to the housing and the raceway. 2. For this purpose, the housing 45 has threaded in it two screws 61 which have milled heads at their upper ends and project 30 downwardly from their heads in such directions that the screw associated with the end of the housing 45 near the bottom of the raceway points downwardly from its head toward that end of the raceway and 35 the other screw points downwardly from its head in the opposite direction. Both screws lie, when the cover 44 is in operative position, inclined at approximately 45° to the vertical so as to bring their heads in a position 40 near the front of the machine and more accessible to the operator than they would be were the screws in a vertical plane. The screws 61 have conical ends to engage the upper surface of the cover and have associated 45 with their heads to co-operate with a recess or a series of recesses in the latter, spring-pressed detents 62 having the same function as those described in connection with the cover mechanism for the front slot 50 4 of the raceway. The cover 44 is upheld against the conical ends of the screws 61 by a leaf spring 64 inserted in a longitudinal slot 66 in the blade and between the upper surface of the slot and a pin 68 fixed in the 55 housing 45 and projecting into the slot. To locate the cover 44 in the housing 45 lengthwise therewith while permitting adjustment of the cover 44 vertically in the housing, the cover is formed with an upright slot 70 entered by a pin 72 projecting from the housing.

The conical end of the screw 61 associated with the housing 45 at the delivery end of the raceway is located substantially at the 60 center of curvature of the curved end of the

raceway so that adjustment of the end of the cover remote from the delivery end of the raceway will have a minimum effect on the relative positions of the raceway and cover at the delivery end of the raceway. 70

Having fully described my invention, what I claim as new and desire to secure by Letters Patent of the United States is:—

1. In mechanism for feeding fastenings, a raceway, a raceway cover, an abutment 75 spaced from the raceway, and a block arranged to be interposed between the abutment and the raceway for retaining the cover in operative position over the raceway.

2. In mechanism for feeding fastenings, a raceway having a slot, a cover for the slot movable between operative and inoperative positions relatively to the slot, a wedge-shaped abutment spaced from the raceway, 85 and a member carried by the raceway and arranged to be interposed between the abutment and the raceway to retain the cover in operative position.

3. In mechanism for feeding fastenings, a raceway, a cover for the raceway, means for mounting the cover on the raceway for movement endwise and transversely of the raceway, and means for securing the cover in operative position on the raceway comprising 90 an abutment spaced from the raceway and a member carried by the cover and adapted to be interposed between the abutment and the raceway, the abutment and the member being relatively constructed and arranged to permit the cover to be moved to inoperative position by manipulation first endwise of the raceway and then transversely of the raceway.

4. In mechanism for feeding fastenings, a raceway, a cover for the raceway, means for mounting the cover on the raceway for movement transversely of the raceway, and means for constraining the cover against such movement constructed to be rendered operative or inoperative by endwise movement of the cover and comprising an abutment spaced from the raceway and formed to present a face inclined toward the raceway in a direction toward the delivery end of the raceway and a member carried by the cover and movable into engagement with said face upon endwise movement of the cover toward operative position on the raceway. 110

5. In mechanism for feeding fastenings, a raceway, a cover for the raceway, means for mounting the cover on the raceway for movement endwise and transversely of the raceway, a spring tending normally to move 115 the cover endwise of the raceway, and means for limiting the movement of the cover by the spring comprising an abutment spaced from the raceway and formed to present a face inclined toward the raceway in the 120

130

- 4 direction in which the cover is moved by the spring and a member movable with the cover and arranged to be interposed between the abutment and the raceway, one of 5 said last-mentioned parts being adjustable to determine variably the limit of endwise movement of the cover on the raceway.
6. In mechanism for feeding fastenings, a raceway, a raceway cover movable endwise 10 along the raceway, and means for retaining the cover in operative position over the raceway constructed and arranged to move the cover transversely of the raceway upon endwise movement of the cover.
- 15 7. In mechanism for feeding fastenings, a raceway having a slot, a cover movable transversely of the raceway toward and from the slot of the raceway, and means rendered operative by movement of the cover toward 20 the slot of the raceway to move the cover endwise of the raceway and to complete the transverse movement of the cover to operative position over the slot of the raceway.
8. In mechanism for feeding fastenings, 25 a raceway, a cover, a shaft on which the raceway cover is mounted for movement transversely of the raceway, a spring on the shaft for moving the cover endwise of the raceway, and means for moving the cover transversely 30 of the raceway upon endwise movement of the cover in one direction.
9. In mechanism for feeding fastenings, a raceway constructed and arranged to be capable by itself of supporting a row of fastenings, a cover for the raceway, yielding 35 means tending normally to move the cover

away from the raceway, and means co-operating with the yielding means to determine the position of the cover with relation to the raceway.

10. In mechanism for feeding fastenings, a raceway, a cover for the raceway, a housing in which the cover is mounted, a spring supported by the housing and tending to move the cover away from the raceway, and 45 independent means for adjustably limiting the movement of the ends of the cover away from the raceway variably to determine the positions of the ends of the cover relatively to the raceway.

11. In mechanism for feeding fastenings, a raceway having a slot, a cover for the slot, a housing in which the cover is mounted, a leaf spring supported in the housing and operable on the cover to move it away 50 from the raceway, means for constraining the cover against endwise movement in the housing, and means co-operating with the spring to determine the position of the cover relatively to the raceway.

12. Fastening feeding mechanism comprising a raceway provided with a slot, a cover for said slot, a shaft by which the cover is carried for movement transversely of the raceway, bearings for the shaft carried by the raceway, a spring arranged yieldingly to urge the cover away from the raceway, and means for adjustably positioning the cover under the influence of said spring.

In testimony whereof I have signed my 70 name to this specification.

JOSEPH GOULBOURN.
